US00D853624S

(12) **United States Design Patent** (10) **Patent No.:** **US D853,624 S**
Hargreaves (45) **Date of Patent:** **** Jul. 9, 2019**

(54) **CORNER ADAPTER**

(71) Applicant: **HGCI, Inc.**, Las Vegas, NV (US)

(72) Inventor: **Doug Hargreaves**, Vancouver, WA (US)

(73) Assignee: **HGCI, Inc.**, Las Vegas, NV (US)

(**) Term: **15 Years**

(21) Appl. No.: **29/596,466**

(22) Filed: **Mar. 8, 2017**

Related U.S. Application Data

(63) Continuation of application No. 29/509,639, filed on Nov. 19, 2014, now Pat. No. Des. 786,492.

(57) **CLAIM**

The ornamental design for a corner adapter, as shown and described.

DESCRIPTION

FIG. 1 is a perspective view of a corner adapter, as viewed from above;

FIG. 2 is a perspective view of the corner adapter shown in FIG. 1, as viewed from below;

FIG. 3 is a top plan view of the corner adapter shown in FIG. 1;

FIG. 4 is a rear elevation view of the corner adapter shown in FIG. 1;

FIG. 5 is a left side view of the corner adapter shown in FIG. 1;

FIG. 6 is a front elevation view of the corner adapter shown in FIG. 1;

FIG. 7 is a bottom plan view of the corner adapter shown in FIG. 1; and,

FIG. 8 is a perspective view of the corner adapter shown in FIG. 1, as viewed from above and in the context of adjoining components thereto.

The broken-line disclosure shown in the views is understood to represent portions of the article in which the claimed design is embodied, but which form no part of the claimed design.

1 Claim, 2 Drawing Sheets
